UNITED STATES PATENT OFFICE.

JOHN EVELYN LIARDET, OF LONDON, ENGLAND.

MECHANISM FOR RECORDING THE MOVEMENTS OF STEERING-GEAR.

SPECIFICATION forming part of Letters Patent No. 673,777, dated May 7, 1901.

Application filed November 23, 1900. Serial No. 37,504. (No model.)

To all whom it may concern:

Be it known that I, JOHN EVELYN LIARDET, a subject of the Queen of Great Britain and Ireland, residing at 16 Hyde Park Gate, in the county of London, England, have invented Improved Mechanism for Recording the Movements of Steering-Gear, (for which I have made application for a patent in Great Britain, No. 20,694, dated the 16th of October, 1899,) of which the following is a specification.

This invention is designed to record chronologically every movement of the rudder of a vessel from starboard to port, and vice versa.

In order to record the movements of the rudder, I attach on the steering-wheel spindle a toothed wheel engaging with a train of wheels. Above the chain-spindle I fix a frame carrying two or more reels and a drum over which a tape passes. Near the said drum I mount a pointer provided with a pencil or other suitable marking device. The said pointer is caused to travel horizontally. This may be done by means of a worm or screw rotated by the aforesaid train of wheels, so that as the steering-wheel is turned the pencil marks on the tape the exact action of the rudder. I provide suitable means for causing the pencil-point to travel in either direction for indicating starboard or port steering.

According to this invention in order to have a chronological record of the above movements of the rudder I provide a timepiece. By means of this timepiece rotary motion is imparted to a wheel or wheels, disk or disks, bearing around its or their periphery or peripheries at regular intervals stamps for recording the time and date. The stamps are kept inked, if necessary, by a ribbon or other suitable means. Means are provided for causing the time-stamps to continually advance and recede while the steering-wheel is being turned, thus automatically recording the time of each movement of the rudder upon the recording-tape before mentioned and also indicating the length of time during which the rudder is stationary. According to one way of effecting this backward-and-forward motion of the time-stamps the said stamps are mounted in the case of the timepiece and the whole case is capable of motion about a hinge. A rod is jointed to the case

and bears at its outer end an eccentric-strap. This strap embraces an eccentric which is turned by the turning of the steering-wheel, so moving the said case backward and forward about its hinge. The length of the said eccentric-rod may be adjusted by means of adjusting-screws or otherwise.

I may mark the actual center line on the tape by means of a marking wheel or disk suitably mounted and supplied with ink.

The apparatus need not necessarily be fitted immediately above the rudder. It may be upon the bridge or at any part of the vessel where convenient.

In order that my said invention may be better understood, I will now proceed to describe the same with reference to the drawings accompanying this specification, in which—

Figure 1 shows a side view of the apparatus, and Fig. 2 an end view of same. Fig. 3 is a detail view of the timepiece and stamp-wheel.

The same characters of reference are employed to denote the same parts in all the views.

a shows the rudder-chain trunk; *b*, table to carry the recording-gear; *c*, arms to support the table *b*; *d*, shaft or spindle to which hand steering-wheel or other appliance or appliances is or are attached; *e*, plumber-blocks for shaft *d*, and *f* chain-wheel keyed to shaft *d* and carrying rudder-chain *g*.

h h' are ratchet-wheels, one of which is fixed to the bevel-wheel *k* and the other to the bevel-wheel *k'*. One ratchet-wheel has its teeth disposed in an opposite direction to those on the other ratchet-wheel.

i shows pawls to the ratchet-wheels *h h'*. *j* represents springs to the pawls *i*.

k k' are bevel-wheels, both of which are mounted loosely on the spindle *d* and engage with the crown-wheel *m*, keyed on the spindle *n*.

o is a worm on the upper end of the spindle *n*.

p is a worm-wheel engaging with the worm *o*.

q is a tape-drum on the same spindle as the worm *p*. *r* and *s* are other tape-bobbins. *t* supports carrying spindles of the drum *q* and bobbins *r* and *s*.

u is a spur-wheel rigidly fixed on the shaft *d*, gearing through wheels *v* and *w* to pinion *x*.

y is a screw-spindle which carries the pinion *x*, and *z* a pencil-carrier traveling on screw-spindle *y* and kept from turning by the rod 11.

12 is a spring pressing upon the pencil in the pencil-carrier *z*.

The action is as follows: When the steering-wheel is turned, the bevel-wheel *k* or the bevel-wheel *k'* (according to which way the steering-wheel is turned) turns the crown-wheel *m*, keyed on the spindle *n*. If the spindle *d* be turned in a certain direction, the bevel-wheel *k* will be turned with it, owing to the engagement of the pawls *i* with the ratchet-wheel *h*. This bevel-wheel *k* imparts motion to the crown-wheel *m*. The bevel-wheel *k'*, being loose on spindle *d*, does not affect the operation; but if the spindle be turned in an opposite direction the bevel-wheel *k'* (turning also in a direction opposite to that in which the bevel-wheel *k* turned) will actuate the crown-wheel *m*, so that this latter turns in the same direction as when actuated by the wheel *k*. This is necessary in order that the ribbon may be always drawn in the same direction no matter which way the steering-wheel is turned. The spindle *n* causes the worm *o* to rotate, thus actuating the worm-wheel *p* and tape-drum *q*. This drum *q* communicates motion by intermediate gearing 13 to the bobbin *r*. The tape is first wound on the bobbin *s* and passes thence over the drum *q* to the bobbin *r*, on which it is wound. The rotation of the shaft *d* is communicated through the wheels *u*, *v*, and *w* and the pinion *x* to the screw-spindle *y*, so that the pencil-carrier *z* is moved backward and forward along the said screw-spindle according to the movement of the steering-wheel, thus recording on the tape the direction of steering.

1 shows the timepiece. 2, Fig. 1, is a wheel turned by the clock mechanism 14 and bearing around its periphery at regular intervals stamps for recording time or times and date. 45 3 is an inking-ribbon. The timepiece is hinged at 4 and a rod 5 is pivoted to it at 6, the other end of the rod 5 being provided with an eccentric-strap embracing an eccentric 7 on the spindle 9, which is turned by means 50 of bevel-pinions 8 from the spindle *n*. 10 is an adjusting-screw to the rod 5. Thus when the shaft *d* is turning the timepiece 1 is regularly rocked to and fro by the eccentric-rod 5, actuated by the bevel-wheels 8, and the 55 stamps on the wheel 2 are brought into and out of contact with the tape on the drum *q*, thus indicating the times at which the records of the various movements of the rudder were made.

60 What I claim as my invention, and desire to secure by Letters Patent, is—

1. In a device of the character described, the combination with the steering mechanism of a vessel; of tape - carrying mechanism, means carried by said steering mechanism for operating said tape-carrying mechanism a

distance proportional to the distance moved by the steering mechanism, mechanism connected to said steering mechanism adapted to receive the oscillatory movements of said steering mechanism, and recording mechanism for marking upon said tape the movements of said steering mechanism, substantially as described.

2. In a device of the character described, 75 the combination with the steering mechanism of a vessel; of tape - carrying mechanism means carried by said steering mechanism for operating said tape-carrying mechanism a distance proportional to the distance moved 80 by the steering mechanism, mechanism connected to said steering mechanism, adapted to receive the oscillatory movements of said steering mechanism, recording mechanism for marking upon said tape the movements 85 of said steering mechanism, and mechanism for marking upon said tape the times of such movements, substantially as described.

3. In a device of the character described, 90 the combination with the steering mechanism of a vessel; of tape - carrying mechanism, mechanism connected to said tape-carrying mechanism for operating said tape in a forward direction from the oscillatory movements of said steering mechanism a distance 95 proportional to the distance moved by the steering mechanism, mechanism connected to said steering mechanism adapted to receive the oscillatory movement of said steering mechanism, and recording mechanism connected thereto for marking upon said tape the movements of said steering mechanism substantially as described.

4. In a device of the character described, 105 the combination with the steering mechanism of a vessel; of tape - carrying mechanism, mechanism connected to said tape-carrying mechanism for operating said tape in a forward direction from the oscillatory movements of said steering mechanism a distance 110 proportional to the distance moved by the steering mechanism, mechanism connected to said steering mechanism adapted to receive the oscillatory movements of said steering mechanism, mechanism connected thereto for 115 recording upon said tape the movements of said steering mechanism, and mechanism for marking upon said tape the times of such movements, substantially as described.

5. In a device of the character described, 120 the combination with the steering mechanism of a vessel; of tape - carrying mechanism, means carried by said steering mechanism for operating said tape-carrying mechanism continuously in one direction during the back-and-forth movements of said steering mechanism a distance proportional to the distance moved by the steering mechanism, mechanism connected to said steering mechanism, adapted to receive the oscillatory movement 125 of said steering mechanism and pencil-carrying mechanism connected thereto, adapted to

record upon said tape the oscillatory movements of said steering mechanism, substantially as described.

6. In a device of the character described, 5 the combination with the steering mechanism of a vessel; of tape-carrying rollers, mechanism for operating said rollers from the movements of said steering mechanism a distance proportional to the distance moved by the 10 steering mechanism, a drum, over which said tape is adapted to pass, gearing connected to said steering mechanism for receiving motion therefrom, and mechanism connected to said gearing adapted to record the movements of 15 said steering mechanism upon said drum over which said tape passes, substantially as described.

7. In a device of the character described, 20 the combination with the steering mechanism of a vessel; of tape-carrying rollers, mechanism for operating said rollers from the movements of said steering mechanism a distance proportional to the distance moved by the steering mechanism, a drum over which said 25 tape is adapted to pass, gearing connected to said steering mechanism for receiving motion therefrom, mechanism connected to said gearing adapted to record the movements of said

steering mechanism upon said tape and mechanism for marking the time of such movements upon said tape, substantially as described. 30

8. In a device of the character described, 35 the combination with the steering mechanism of a vessel; of a movable tape, mechanism for operating said tape from said steering mechanism, means for recording the movements of said steering mechanism upon said tape, and a wheel operated by a clock-motor, 40 said wheel carrying stamps upon its periphery, and means for bringing said stamps into contact with said tape, substantially as described.

9. In a device of the character described, 45 the combination of steering mechanism, mechanism including a recording-tape for recording the movement thereof, said last-named mechanism being moved a distance proportional to the distance moved by the steering mechanism and mechanism operated by said 50 steering mechanism for recording the time of such movement, substantially as described.
